(57) **CLAIM**

The ornamental design for a router table adapter base plate, as shown and described.

DESCRIPTION

FIG. 1 is a perspective view of the top of a router table adapter base plate in accordance with the present invention; FIG. 2 is a side view of the router table adapter base plate; FIG. 3 is a perspective view of the bottom of the router table adapter base plate;

FIG. 4 is a top view of the router table adapter base plate; and,

FIG. 5 is a bottom view of the router table adapter base plate. A router table adapter base plate has various groupings of hole patterns, some of which are countersunk, and some of which are counterbored. Lettering on the base plate identifies the group that a hole belongs to. Some of the holes on the bottom side have a polygonal inset.
